EUGENE WILLIAM SAWTELLE, OF SACRAMENTO, CALIFORNIA.

WATER-HEATER.

950,516.

Specification of Letters Patent. Patented Mar. 1, 1910.

Application filed March 10, 1909. Serial No. 482,627.

To all whom it may concern:

Be it known that I, EUGENE WILLIAM SAWTELLE, a citizen of the United States, residing at Sacramento, in the county of Sacramento and State of California, have invented certain new and useful Improvements in Water-Heaters, of which the following is a specification.

My invention relates to improvements in water heaters and especially to that class used for heating a supply of water for domestic purposes by means of gas; and the objects of my invention, among others which will become apparent, are to provide a heater from which the settling of water charged with sediment may readily be removed not only from the tank but also from the coils; to provide an arrangement of heating coils that will supply the maximum amount of hot water with the minimum expenditure of gas, and to provide certain novel arrangements of pipes and connections as will be further explained.

A practical embodiment of my invention is represented in the accompanying drawings forming part of this specification, in which similar figures of reference indicate corresponding parts throughout.

The specification is in such clear and concise terms that anyone familiar with the art to which this invention applies may readily understand it and be able to construct the same, reference being also had to the drawings.

Figure 1 is a vertical sectional view showing certain parts in side elevation of the water heater forming the basis of my invention. Fig. 2 is a sectional view taken at the dotted line o—o of Fig. 1 to show the T 15' and the outlet 19.

In Fig. 1, 1' is a stand for supporting the boiler; 1 is the outer shell of the boiler; 2 is an open ended central tube or flue concentric with the shell, the upper end of which terminates in the head 3 and the lower end terminates in the frusto-conical bottom 4; 5—5 is a double spiral water heating coil vertically arranged within the flue 2, the terminals of said coil connecting with 50 Y's 6—6.

8 is a gas burner located below the coils and 10 is a chimney for conveying off any gas or fumes.

The water supply is admitted into the tank through the cock 11 situated near the lower part of the tank; about on a level

with this and at any point in the periphery of the tank but preferably opposite to it, is a pipe connection 12 which conducts the water near the lower part of the boiler to 60 the lower end of the coil 5 through the pipes 13 and 13' and their auxiliary connections. At the lowest point on the pipes 13 and 13' is a drain cock 17 and between this cock and the connection 12 is a stopcock 18. 65 When it is desired to clear the coil of any sediment, the cock 18 is shut off and the cock 17 opened, it being understood that the supply-cock 11 is also open.

At the lowest practical point in the tank 70 is placed a cock 15 supplied from the main pipe 16 as indicated, and within the tank and connected to said cock by suitable fittings is a T 15' so placed that when the cock 15 is opened (the cock 11 now being 75 closed) the stream of water will be divided, part going around the bottom of the tank one way and part the other, see Fig. 2. It is obvious that when the drain-cock 19 is opened, any deposit or settling which may 80 have collected in the pocket formed by the union of the sides of the tank and the frusto-conical bottom will be washed out. When it is desired to clear the bottom of the boiler, the cock 11 should be closed, and the two 85 cocks 15 and 19 opened. The supply cock 11 is placed above the cock 15 so that as the fresh supply of water is injected into the tank it will not agitate any settling or deposits therein. By this arrangement of 90 drains it is possible to keep the tank and coils free from settling which have proven so disastrous in certain parts of the country to water heaters of this class.

Near the upper end of the tank is a sleeve 95 20 connecting the outer shell of the boiler with the flue 2; this sleeve is to form a passage-way for the introduction of the pipe 21 connecting the upper discharge end of the coils 5 with the pipe 22. The outer end of 100 this sleeve is plugged by the bushing 20'. In the lower part of this pipe 22 is placed a T 23 with suitable connection to the tank, and the upper end of 22 is connected by another T 24 to the upper head 3 of the 105 tank; and the hot water delivery pipe 25 is connected to this T, all as indicated.

The operation will then be as follows: Water passing through the pipes 13 and 13' (the cock 18 being open) will enter the lower 110 end of the coil 5 and become instantly heated, and rising, will pass into the general cir-

ulation of the tank through the T's 23 and 24 and their connecting pipes 21 and 22, tending to heat the entire contents of the tank quickly. When the hot water delivery pipe 25 is opened by means of a valve connected with the hot water delivery service, the hot water in the coils will be delivered first, passing directly through the pipes 21, 22 and 25 and afterward the water in the upper end of the tank will pass out through the T's 24 and 23. With this simple arrangement of pipes, it is possible to obtain a quantity of hot water quickly or a larger supply in a short period of time. But in order that the proper circulation of water may be carried on in the tank and coils, it is necessary that they be kept free from settling which form when the water supply is charged with considerable sediment. If the tank is not in constant use, sediment will collect in the coils and bottom of tank, and when heat is applied will cause the sediment to harden and thus obstruct the proper passage of water. Should this continue, the pipes may become completely closed, thus causing considerable damage; this condition is overcome by the system of drain cocks and valves hereinbefore fully explained.

While I have shown and described a frusto-conical bottom boiler, I do not wish to claim such broadly, as the arrangement I have shown can be used equally well with a flat bottom boiler when the distance between the shell and the inner flue is not very great. The drawings show a double spiral water coil; this may be a single coil but I prefer to use the double coil as it exposes a greater surface to the action of the heat. It is, therefore, to be noted that various changes may be made in the form, proportion and minor details of construction without in any way departing from the principle or sacrificing any of the advantages of this invention.

I am aware that water heaters having heating coils is not new, but

What I claim as new and desire by Letters Patent to secure, is—

1. In a water-heater suitably supported, the combination of a tank having an upper head and a frusto-conical bottom and an open ended inner flue concentrically fixed therein, one end terminating in the upper head and the other in the frusto-conical bottom, and having a sleeve connecting the outer shell of said tank near its upper end with the above

mentioned flue; a coil vertically disposed within said flue; a pipe leading from the bottom of said coil around the lower part of the tank and connected to the tank on the outside near its lower end; a pipe leading from the upper end of the aforesaid coil through the hereinbefore mentioned sleeve; a T connecting this last mentioned pipe to the tank on the outside just above the sleeve; a continuation of this same pipe and a second T connecting the same to the head of the tank; a hot-water delivery pipe connected to this last mentioned T; a cold-water supply pipe connected to the tank at two points, the one above the other, near the bottom thereof; and a gas burner located below the water coil.

2. In a water heater suitably supported and having a drain-cock 19, the combination of a tank having an upper head and a frusto-conical bottom and an open ended inner flue concentrically fixed therein, one end terminating in the upper head and the other in the frusto-conical bottom, and having a sleeve connecting the outer shell of said tank near its upper end with the above mentioned flue; a coil vertically disposed within said flue; a pipe leading from the bottom of said coil around the lower part of the tank and connected to the tank on the outside near its lower end, said pipe being provided with a drain cock 17 and a stop cock 18; a pipe leading from the upper end of the aforesaid coil through the hereinbefore mentioned sleeve; a T connecting this last mentioned pipe to the tank on the outside just above the sleeve; a continuation of this same pipe and a second T connecting the same to the head of the tank; a hot-water delivery pipe connected to this last mentioned T; a cold-water supply pipe 16 connected to said tank at two points, the one above the other, near the bottom thereof, the upper connection being provided with a stop-cock 11 and the lower connection being provided with a stop-cock 15 and terminating within the tank in a T 15'; and a gas burner located below the water coil.

In testimony whereof I have signed my name to this specification in the presence of two subscribing witnesses.

EUGENE WILLIAM SAWTELLE.
